UNITED STATES PATENT OFFICE.

BRUCE CLARK WHITE, OF NEW YORK, N. Y., ASSIGNEE TO FEDERAL ELECTRIC COMPANY, OF CHICAGO, ILLINOIS, A CORPORATION OF ILLINOIS.

GEARING FOR WASHING MACHINES.

Application filed June 3, 1920. Serial No. 386,267.

To all whom it may concern:

Be it known that I, BRUCE CLARK WHITE, a citizen of the United States, and a resident of New York city, in the county of 5 New York and State of New York, have invented certain new and useful Improvements in Gearing for Washing Machines; and I do hereby declare that the following is a full, clear, and exact description there- 10 of, reference being had to the accompanying drawings, and to the letters of reference marked thereon, which form a part of this specification.

This invention relates to an improvement 15 in gearing for washing machines and consists of the matters hereinafter described and more particularly pointed out in the appended claims.

My invention relates to a gearing for 20 washing machines, in which a rotating crank is connected to an oscillating operating arm to impart a rotary, oscillatory movement to the operated member, as the drum or cylinder, of a washing machine.

25 When a crank is connected by a pitman to drive an oscillating arm, the rate of movement of the oscillating arm will be relatively slower at successive points in its path when moving in a direction away from 30 the position of the crank orbit than at the corresponding points in its path, beginning from the other end of said path, when the oscillating arm is moving towards said crank orbit. This is due to the fact, capable 35 of ready demonstration, that in the movement of the oscillating arm away from the crank orbit, its rate of movement is in proportion to the arithmetical difference between the versed sines of the angles of the 40 crank and of the pitman, whereas on the return movement of the oscillating arm toward the crank orbit, its rate of movement is in proportion to the arithmetical sum of the versed sines of said angles. The move- 45 ment of the oscillating arm thus lacks uniformity of acceleration in the two direc- 50 tions and while slow enough at that end of its path of movement nearest to the crank orbit, the movement is too fast and has too sudden and rapid acceleration upon the reverse, at the other end of its path of move- 55 ment.

My invention is designed to correct this evil and to produce a substantially uniform slowing down and a substantially uniform,

gradually increasing speed after reversal, at both ends of the path of movement of the oscillating arm.

Thus one of the objects of the invention is to provide a gearing which is adapted to 60 so translate the rotary movement of a crank arm into an oscillatory movement of an operating arm and of the oscillatory washing machine member actuated thereby, that the oscillatory movement shall be uniformly 65 slow at both limits of its oscillation and shall have a substantially uniform rate of acceleration in both directions to and from the more rapid rate of movement intermediate said limits of oscillation. This and 70 other objects and advantages of the invention will be more particularly pointed out as I proceed with my specification.

The present invention is a species of the generic invention disclosed in an applica- 75 tion describing a novel gearing for washing machines, filed by me on the 1st day of May, 1920, Serial Number 378,072.

In the drawings:—

Figure 1 represents a side elevation of a 80 washing machine having an oscillatory cylinder and provided with an operating gearing embodying my invention.

Figures 2 and 3 are detail views of the 85 gearing on an enlarged scale, representing the parts of the gearing in different positions.

Figures 4 and 5 are diagrammatic views 90 which will be more particularly described in the specification.

Referring to that embodiment of the invention illustrated in the drawings:—10 indicates the body of a washing machine, which is of any suitable construction. It includes a tub 11 to contain the water for 95 washing the clothes and an oscillatory cylinder 12, which is the receptacle for the clothes to be washed. 13 indicates the usual wringer mounted on the tub.

The cylinder or receptacle 12 is mounted 100 in the tub in any convenient manner so as to be capable of an oscillatory movement of a predetermined amplitude. The gearing for imparting movement is all mounted on a bar or frame 14, which is attached to the 105 upright legs 15—15 at one end of the tub.

The gearing is preferably enclosed in a gear case 16, provided between the legs 15—15 and the adjacent end of the tub 11,—a door 17 (shown in dotted lines in Fig. 1) hinged 110

to one leg of the tub body, forming a closure for the gear case.

The oscillatory movement is imparted to the tub by means of an operating arm 18, fixed to a stud shaft 19, which has rotative bearing in a standard 14^a rising from the bar 14. Said stud shaft has its axis coincident with the axis of the oscillatory receptacle 12, and is capable of operative connection therewith in a familiar way not necessary to be described herein.

At one side of the operating arm 18 and as illustrated, somewhat below the same, is located a worm gear 20, which is suitably mounted on the bar or frame 14. Said worm gear is in a plane at right angles to the axis of the stud shaft 19 and is driven by a horizontal worm 21 on a shaft 22, which is in line with and is operatively connected to a shaft 23 of a motor 24. The motor 24 is attached to and supported by the bar or frame 14. A friction coupling mechanism 25, is preferably interposed between the shaft 22 and the motor shaft 23, in order to relieve the motor shaft in case the gearing or the parts driven thereby become obstructed or otherwise prevented from operation, so as to put too great a load on the motor.

The wringer 13 is driven by an upright shaft 26, which is connected to the worm 21 by a suitable worm gear.

28 indicates a crank pin on the worm gear, and 29 indicates the pitman which is designed to drive the operating arm 18. A radius arm 30 is pivoted on the standard 14^a to a horizontal pin 31. Said pin, as illustrated, is positioned below and a little to the right of the stud shaft 19. The end of the radius arm 30 is pivotally connected by 40 a pin 32, to the pitman 29.

Thus far, the present form of the gearing is the same as that described in my previous application hereinabove referred to. The present form differs from the former in that, 45 while in the former the radius arm and the operating arm were connected by a link, in the present form the radius arm and the operating arm have a pin and slot connection; that is to say, the pin 32 which connects the radius arm 30 to the pitman 29, engages in an arcuate slot 33 in the operating arm.

The rotary movement of the crank pin 28 will impart, through the pitman 29, an oscillatory movement to the radius arm 30, and the radius arm through its pin and slot connection with the operating arm 18, namely, the pin 32 and the slot 33, will impart an oscillatory movement to the operating arm 18. It will be manifest from an inspection of Figures 2 and 3, that on account of the pin and slot connection of the pin 32 to the operating arm 18, the angle through which the operating arm 18 is oscillated (indicated 65 by the arc "a") is much greater than the

angle through which the radius arm is oscillated (indicated by the arc "b").

In designing the parts comprising the gearing and as more particularly indicated in the diagrammatic views shown in Figures 2 and 3, the angle "a" is approximately 130°, while the angle "b" is approximately 60°. An oscillation having an amplitude of 130°—namely, 65° to one side of the vertical and 65° to the other side of the vertical, is about that required by the cylinder 12 in a washing machine of the kind described. The lengths of the several parts may be given in the terms of the crank arm (namely, the arm "r" or radius of the circle "z" in which the crank pin 28 rotates) as a unit, substantially as follows:

The pitman 29 is of a length equal to four times the length of the crank arm; the radius arm is twice the length of the crank arm; and the operating arm 18 is of such length as to contain the arcuate slot 33 which has a radius of $\frac{1}{2}$ of the length of the crank arm,—the manner of determining the position of said slot being as follows:

In locating the several centers, a line $x-x$ may be drawn through the center of the crank pin circle to represent the median position of the pitman 29. The permitted length of the crank or the radius "r" of the crank pin circle is then determined and after the circle of the crank pin 28 is described, the length of the pitman is laid out on the line $x-x$ to the right (as illustrated) from both sides of the crank pin circle, to give the points on said line indicating the limits of movement of its right hand end. The line $y-y$ is then drawn at right angles to the line $x-x$ through the point on the line $x-x$ midway between said limits. With a point "s" on the line $y-y$ as a center, and a radius 18^a of assumed length (in this case 1 $\frac{1}{2}$ times the length of the crank arm) the arc "a" is described. With a point "i" on the line $y-y$ as a center, and a longer radius, the arc "b" is described,—this representing the arc through which the pin 32 on the radius arm 30 is to oscillate. In the present example, the radius arm selected, as already pointed out, is twice the crank arm or the radius of the circle of the crank pin 28 and the position of its center on the line $y-y$ is such that the arc described about said center is approximately 60° between the points where it intersects the line $x-x$.

With a point "d" (which is the central position of the pin 32 when at its left hand limit of movement), as a center, and a radius 33^a (in this case of a length 1 $\frac{1}{2}$ times the length of the crank arm) an arc "e" is described to intersect the assumed arc "a". With the said point of intersection "e" as a center and with the radius 33^a, the arc "f" may be then described,—this being the designed arc 130

of travel of the pin 32 with reference to the operating arm 18. The operating arm 18 may then be formed to provide and include an arc of this radius to guide the pin 32.

5 From an examination of Figures 4 and 5, it will be apparent that the center of the pin 32 will move in the arc "b" and that by reason of its pin and arcuate slot connection with the operating arm 18, in thus 10 moving it will impart to said arm an oscillating movement, the amplitude and rate of which may be measured by the movement of the point "e" on the imaginary arc "a" — the angle of this arc being equal to the 15 angle of the arc "a" which is apparently the arc through which the arm 18 is moved.

In Figures 4 and 5, I have shown diagrammatically the relative positions of the several parts of the gearing for different 20 angles of movement of the crank from 0° to 360°. To save confusion, the position of the parts from 0° to 90° are shown in Figure 4 and the position from 180° to 270° are shown in Figure 5. The 0° position of 25 the crank corresponds to the left hand limit of movement of the pitman, while the 180° position of the crank corresponds to the right hand limit of movement of the pitman. Figure 4 thus represents the movement 30 of the operating arm and radius arm away from the crank orbit, while Figure 5 represents the movement of the operating arm and radius arm towards the crank orbit.

35 While in describing the invention, I have referred to details of construction and arrangement of parts, the invention is no way intended to be limited thereto, except in so far as may be pointed out in the appended 40 claims.

I claim as my invention:—

1. A gearing for washing machines comprising; an operated member capable of a 45 rotary, oscillatory movement; a rocker arm adapted for actuating said operated mem-

ber; a pivoted radius arm of a length greater than that of the rocker arm; means providing a pin and slot connection of said radius arm to said rocker arm, the slot being formed in an arc of a radius and being positioned relative to the arm carrying the pin, both predetermined to oscillate the operated member at a rapidly accelerated rate from the points of reversal to the mid point of the oscillatory movement, 50 with the rates of acceleration from each reversal point substantially the same, and the rates of movement approaching and leaving both points of reversal, equally slow, avoiding shock at reversal; and means 55 for driving said crank.

2. A gearing for washing machines comprising; an operated member capable of a 60 rotary, oscillatory movement; a rocker arm adapted for actuating said operated member; a pivoted radius arm of a length greater than that of the rocker arm; a pin 65 connecting the radius arm to the rocker arm; the rocker arm being provided with an arcuate slot in which said pin has bearing and movement, the radius of the arc of said slot and the position of said slot being both predetermined to oscillate the operated member at a rapidly accelerated 70 rate from the points of reversal to the mid point of the oscillatory movement, with the rates of acceleration from each reversal point substantially the same, and the rates of movement approaching and leaving both 75 points of reversal, equally slow, avoiding shock at reversal; and means for driving 80 said crank.

In testimony that I claim the foregoing as my invention, I affix my signature in the presence of two witnesses, this 26th day of 85 May, A. D., 1920.

BRUCE CLARK WHITE.
